(57)

CLAIM

The ornamental design for a foldable spoon, as shown and described.

DESCRIPTION

The patent or application file contains at least one drawing executed in color. Copies of this patent or patent application publication with color drawing(s) will be provided by the Office upon request and payment of the necessary fee.

1.1 : Front

1.2 : Back

The surfaces and portions of the foldable spoon that are not shown in the drawings or described in the specification form no part of the claimed design.

**1 Claim, 2 Drawing Sheets
(2 of 2 Drawing Sheet(s) Filed in Color)**
